(57) **CLAIM**

I claim the ornamental design for a comb, as shown and described.

DESCRIPTION

FIG. 1 is a left side front perspective view of an example comb showing my design.

FIG. 2 is a rear elevation view of the comb illustrated in FIG. 1. The front elevation view is identical to the rear elevation. FIG. 3 is a top plan view of the comb illustrated in FIG. 1. FIG. 4 is a bottom view of the comb illustrated in FIG. 1. FIG. 5 is a right elevation view of the comb illustrated in FIG. 1; and,

FIG. 6 is a left elevation view of the comb illustrated in FIG. 1.
